SAFETY WINDOW CHAIR

Filed Nov. 6, 1922

2 Sheets-Sheet 2

UNITED STATES PATENT OFFICE.

FRANK ADLER, OF BROOKLYN, NEW YORK.

SAFETY WINDOW CHAIR.

Application filed November 6, 1922. Serial No. 599,353.

To all whom it may concern:

Be it known that I, FRANK ADLER, citizen of Russia, and resident of Brooklyn, in the county of Kings and State of New York, have invented certain new and useful Improvements in Safety Window Chairs, of which the following is a specification.

This invention relates to improvements in window chairs, brackets or jacks, such as may be temporarily attached to the walls of a window or like opening and extended outwardly therefrom to safely support an individual performing duties exterior of the window.

15 One of the objects is to provide a device which is readily adjustable to windows of varying widths and in such manner as to avoid abrasion of the window sash, frame or wall of the building.

20 Another purpose is to produce a strong but light device for the purpose, which can be readily applied or removed without tools of any sort or extraneous fastening means of any kind, and, when not in use is capable of 25 being compactly folded for storage and transportation.

These and other corresponding aims, becoming apparent as the description proceeds, are accomplished by the novel design, construction and arrangement of parts hereinafter described and shown in the drawings relating thereto, and in which:

Figure 1 is a general perspective view showing an embodiment of the invention, extended in operative position and illustrating its application.

Figure 2 is a plan view of the same looking from the top.

Figure 3 is a transverse sectional view 40 taken on line 3-3 of Figure 2.

Figure 4 is a similar view of the same but showing the parts of the device in a close folded position.

Figure 5 is an enlarged fragmentary view 45 of one of the inner adjustable support bars and its associated elements, parts being broken away to show the construction.

Figure 6 is a partial side and sectional view of the adjustable back support and allied parts, these sections being taken on line 50 6-6 of Figure 7.

Figure 7 is a partial front and sectional view of the same.

Fig. 8 is a fragmentary view of the pan and the means for supporting it, the section being taken on line 8-8 on Fig. 2.

As shown in the drawings, the wall of a building is designated by the numeral 15, the same having a window opening 16, an extending sill 17 and frame 18, in which glazed sashes 19 are operatively mounted, the construction being purely conventional in type, forming no part of the invention.

A platform or seat 20, preferably made of sheet metal having down turned flanges 21 and 22, respectively, at its sides and rear, is similarly flanged at the front, this flange 23 extending the full width of the platform and formed to present a concave outer face, the lower portion of the flange being bent to produce a parallel ledge 24.

A U shaped elongated clip 25 having a thickened front 26, is secured by rivets to the upper surface of the platform and the ledge 24, there being a substantially circular opening between the clip and flange in which are slidably received stout tubes 27, held when in adjustment by set screws 28.

Secured to the outer ends of the tubes 27 are cylindrical buffers 29 and midway in the length of the tubes are secured rigid brackets 30 having extending stems, also encircled with cushion buffers 31 adapted to rest against the window frame centering the device and preventing it from moving laterally, while the ends of the tubes 27 engage the window frame sides adjacent to their inner surfaces to prevent outward movement of the platform, the buffers obviating any damage to the parts against which contact is made.

A channel iron 32 is secured to extend transversely across the front end of the platform at its lower side and carried by the channel is a cushion 33 suited to rest upon the window sill.

The side flanges 21 are folded upward closely upon themselves, as at 34, and formed with lugs 35 carrying a rod 36 acting as a pivot for a pair of support bars 37 arranged on the outer surface of the sides of the platform and bent at their lower ends 38 to extend towards the window but considerably below it.

Mounted in these ends is a rod 39 encased in a rubber tube or roller 40 suited to rest

against the wall 15 and held firmly in adjusted position by the following means.

The upper extending ends of the bars 37 have secured to them plates 41 carrying box-like structures 42 between the sides of which rigid pins 43 are fixed, the same engaging in any of the several notches 44 formed in articulate levers 45.

Said levers are pivoted at 46 to the sides 10 of the platform 20 at points near the channel 32, and connected at their free ends by a transverse bar 47 having bent ends riveted to the ends of the bars 45.

In order to maintain the notches 44 in positive engagement with the fixed pins 43, keeper slides 48 are provided to extend over the upper edges of the bars 45, said slides being housed in brackets 49 fixed to a backing plate 50 the same being flanged on each 20 of its four edges and extending between the box elements 42 from side to side of the structure and raised from the platform as shown, there being openings 51 in the backing plate through which angular projections 35 52, formed with slides 48 extend for convenience in actuating the keepers, all these several parts being carried by the bars 37.

Centrally in the platform 30 is a longitudinal opening 53 having downturned flanged edges utilized, in addition to strengthening the plate, to carry pivots 54 hingedly engaging a plate 55 also having downturned edges and resting on an abutment 56 formed with the corresponding edge 35 of the platform.

Formed in the plate 55 is an opening 57, its surrounding edges being folded closely to present smooth surfaces to act as a handle by which the device may be carried and by 40 which the device may be placed into or removed from the window opening, an additional raised handle 58 being secured permanently to the platform near its curved outer edge 22.

45 When the structure is folded into the position indicated in Figure 4, a latch 59, pivoted to one of the flanged edges of the platform, may be engaged in a slot 60 in the upper end of the adjacent box-like element 50 42, thus holding the device in closed or folded position.

In operation, the hook or catch 59 is disengaged, the platform and its rear attachments passed through the open window until 55 the buffers 29 on the extended rods make contact with the inner sides of the window frame, the brackets 31 being adjusted to touch the sides of the frame below the sash, and the set screws 28 tightened to prevent 60 further movement of the bars.

In that position the cushion 33 rests upon the window sill and the roller 40 adjusted to engage the outside wall of the building, this being accomplished by grasping the 65 plate 55 by the hand hole 57 raising the

plate into contact with the backing 50, turning the latter outwardly, after which the backing is pressed out as far as it will go, the back 50 moving in unison with the roller and the arms 45 acting as guards at the 70 sides of the platform.

When these adjustments have been made they are positively held by the detent slides 48, thus affording a secure and safe structure for the purposes set forth. In addition a pan 61 may be attached to the platform sides for convenience in carrying articles used by the operator, by means of tongues 62 fitting within the clip 63 fastened to the flange 21.

Obviously to remove the device from the window opening it is but necessary to grasp with one hand the plate 55 by the hand hole 57 and raise it until it has reached the position shown in dot and dash lines in Fig. 3 85 which will be the angular direction of the pull or application of power from the shoulder of the operator, and to grasp with the other hand the front of the platform 26. This of course obviates the necessity of the operator leaning out of the window to lift in 90 the device and thus eliminates the possibility of accident.

However as changes of construction could be made within the scope of the invention, it is intended that all matter contained in the foregoing description or shown in the drawings shall be regarded as illustrative rather than in a limiting sense.

Having thus described my invention, what I claim as new and desire to secure by Letters Patent, is:—

1. A window chair comprising a sheet metal platform having flanged edges, alined bars carried telescopically at the front of said platform adapted to engage the walls 105 of the window frame on each side thereof when extended, means carried by said bars for centering said platform relative to the window opening, a pair of lever arms pivoted to the platform, a roller carried by said arms to make contact with the wall below the window opening to support the outer end of said platform, means for maintaining said arms in adjustment, and a backing for said platform carried by said arms above 110 the pivot.

2. A window chair comprising a sheet metal platform, means for anchoring said platform to the frame of a window, means for locating the platform relative to the 120 window opening, arms at the side of the platform intermediate their ends, the greater length of the arms being below the pivots, a roller carried at their lower ends, a backing at their upper ends, curved levers pivoted to the sides of said platform, said levers having teeth in their concave surfaces, pins carried by said arms, engageable in said teeth, and means for confining the pins when 125 adjusted between said teeth.

3. A window chair comprising a sheet metal platform having flanged edges, means for adjustably engaging said platform to a window frame, adjustable supports at the sides of the platform, a plate pivoted to cover an opening in said platform, said plate having a handle opening, and a handle fixed to said platform by either of which it may be carried.

Signed at New York in the county of New York and State of New York this 1st day of November A. D. 1922.

FRANK ADLER.
